UNITED STATES PATENT OFFICE.

CLARENCE E. BONNER, OF NEW YORK, N. Y., ASSIGNOR, BY MESNE ASSIGNMENTS, TO BONNER-CHARTER CORPORATION, OF DOVER, DELAWARE, A CORPORATION OF DELAWARE.

ENGINE CONSTRUCTION.

Application filed April 28, 1921. Serial No. 465,176.

This invention relates to a new and improved engine construction, and more particularly to an improvement in the design of internal combustion engines of the sleeve valve type.

In sleeve valve engines considerable difficulty is involved in mounting and dismounting the sleeve valve and its operating member, and it is essential for ease of assembly that the sleeve valve be removable upwardly from the cylinder block in order to avoid the necessity for completely tearing down the engine when cleaning or adjusting the valves. It is highly desirable for the same reasons that the inner cylinder member, where such a member is provided, be removable in the same manner. The inner cylinder member must be accurately retained in place and be positively centered in order to secure the proper operation of the engine, and it is very necessary that the inner cylinder be positioned in such manner as to permit longitudinal expansion thereof due to heating. It has been found highly desirable that the sleeve valve extend substantially the full length of the cylinder and be driven and oiled from below in order to avoid complications in the castings and in the engine design. These long sleeves have also proved especially desirable in maintaining a close seal at the ports.

The expansion of the various members caused by heating in engines of this type, where the inner cylinder is surrounded by a sleeve valve, often causes binding and prevents proper operation. Due to the varying temperatures of the several elements when the engine is operated and their necessarily very close interfit, it is highly important that the temperature expansion be taken care of in some manner.

It is an object of the present invention to provide an internal combustion engine of the type described in which the inner cylinder and sleeve valve are removable from the upper end of the cylinder block and in which the sleeve gear is integrally formed upon the sleeve and within the contour thereof.

It is a further object to so proportion the sleeve drive gear that the sleeve may be removed without removal of the drive gear.

It is an additional object to provide a guide for the lower end of the cylinder,

formed integrally with the cylinder casting. 55

It is also an object to form the sleeve valve and the cylinder block of materials having different coefficients of expansion so that binding due to heating expansion is eliminated. 60

Other and further objects will appear as the description proceeds.

Broadly defined, my invention comprises an engine consisting of a cylinder block having openings therein adapted to receive inner cylinder members. The blocks are provided with shoulders at their upper ends adapted to engage flanges upon the inner cylinder members and are provided adjacent the lower end of each inner cylinder with a shoulder adapted to serve as a guide for the cylinder. The sleeve valve is fitted between the inner and outer cylinder members and bears upon a guide ring supported upon the guide shoulder. The sleeve valve has gear teeth cut within its contour adjacent its lower end and associated with a drive gear. While the three members (the inner and outer cylinders and the sleeve valve) may be formed of any desired metals whose coefficients of expansion bear the necessary relation, I preferably form the cylinder casing of an aluminum alloy, the sleeve valve of steel, and the inner cylinder of cast iron. 70 75 80 85

I have illustrated a preferred embodiment 85 of my invention in the accompanying drawings, in which—

Figure 1 is a vertical section illustrating a one-cylinder engine made according to my invention; 90

Figure 2 is a horizontal section of Figure 1 taken on line 2—2; and

Figure 3 is a view of the sleeve valve member partly broken away.

The engine comprises the lower crank case member 5 to which is fitted the cylinder block 6. The crank shaft 7 passes between these two members and is retained in bearings 8 and 9. The left end of the engine is closed by the cover plate 10. The flywheel 11 is secured to the right end of the crank shaft. 95 100

The inner cylinder member 12 is fitted into the cylinder block and is provided at its upper end with the flange 13 engaging the shoulder 14 on the cylinder block. The cylinder block is provided adjacent the lower end of the cylinder with the inwardly ex-

- tending shoulder 15 which engages the cylinder and serves as a guide therefor. Upon the shoulder 15 is a hardened steel guide ring 16 which closely engages the inner cylinder member and which supports the sleeve valve member 17. The piston 18 fits within the inner cylinder member 12 and is connected to the crank shaft 7 by the connecting rod 19.
- 5 As shown in Figure 3, the sleeve valve member 17 is provided with the ports 20 and has its lower outer portion cut to form the gear 21. As best shown in Figure 2, this gear 21 is engaged by the worm gear 22 carried by the shaft 23. This shaft 23 carries the gear 24 which is driven from the gear 25 mounted upon the crank shaft. These gears are preferably connected by a silent chain (not shown).
- 10 The inner cylinder member 12 is provided with ports 26 adapted to coact with the sleeve valve ports and with ports in the cylinder case. The cylinder head member 27 is provided with the inwardly extending 15 central portion 28 which closely fits the interior of the cylinder 12. The member serves to retain the inner cylinder members in place and the latter serves to hold in place the sleeve valve. The cylinder head 20 is secured to the cylinder block by the bolts 29 and nuts 30, a paper or other gasket being used if desired to secure a tight joint for the water jacket.
- 35 In assembling the cylinder and valve structure, the valve sleeve drive gear may be already in place. The hardened steel guide ring 16 is first passed within the cylinder opening, resting upon the shoulder 15. The sleeve valve member 17 is then inserted in the cylinder block, it being necessary of course to insert it in such rotary position relative to the drive gear 22 as to properly time the opening and closing of the ports. In order that this member may 40 be inserted and withdrawn without removal of the gear 22, the teeth upon the gear are cut through the lower edge of the gear. The inner cylinder member 13 is next inserted, the lower portion being guided by the shoulder 15 and the upper portion being accurately centered not only by its close fit with the sleeve valve, but more positively by the exact interfit of the flange 13 with the shoulder portion 14 in the cylinder block. The 45 cylinder head member 27 is then put in place, its lower extension serving as addi-

tional means for accurately locating the cylinder. In removing the several elements, they are taken out in the reverse order.

This form of design makes it possible to 50 remove and replace the several elements without any extended taking down of the engine proper. Preferably the outer cylinder block 6 is formed of aluminum alloy which has a comparatively high coefficient 55 of expansion and the sleeve valve member 17 is formed of steel having a lower coefficient of expansion, while the inner cylinder 12 is preferably formed of the usual gray cast iron having a still lower coefficient 60 of expansion. These variations in coefficients of expansion are necessary to take care of heat expansion, since the innermost member is heated at a higher temperature than the outer members, not only because it 65 is closer to the source of heat, but because the outer members are cooled by the water jacket. This particular combination of 70 metals, or any similar combination of metals having the same relation as regards expansion and capable of withstanding the necessary strains, therefore aids very materially in eliminating any strains or binding due to 75 heat expansion.

I claim:

In an engine construction, an outer cylinder block, an inner cylinder consisting of a tubular member open at both ends, ports cut in the sides of the cylinder, a circumferential flange on the upper end of said inner cylinder engaging a recess in the upper face of the cylinder block whereby the upper end of the cylinder is centered relative to the block, an inwardly extending circumferential shoulder on the outer cylinder adjacent the lower end of the inner cylinder and adapted to maintain the lower end of the inner cylinder in fixed relation to the outer cylinder, a bearing ring carried by said shoulder, a valve sleeve carried between the inner and outer cylinder members and having its lower edge bearing upon the ring, the sleeve being relatively thick and having gear teeth cut therein adjacent the lower edge, and a gear engaging said teeth to rotate the sleeve, the lower edge of the sleeve being formed, to permit removal of the sleeve upwardly from the block without removal of the coacting gear.

Signed at New York, New York, this 110
22nd day of April, 1921.

CLARENCE E. BONNER.
